UNITED STATES PATENT OFFICE.

JACOB KAUFMANN, OF PHILADELPHIA, PENNSYLVANIA, ASSIGNOR TO STEEL HEDDLE MANUFACTURING COMPANY, OF PHILADELPHIA, PENNSYLVANIA, A CORPORATION OF PENNSYLVANIA.

REED FOR LOOMS.

1,294,671.

Specification of Letters Patent.

Patented Feb. 18, 1919.

Application filed September 15, 1917. Serial No. 191,515.

To all whom it may concern:

Be it known that I, JACOB KAUFMANN, a citizen of the United States, residing at Philadelphia, in the county of Philadelphia and State of Pennsylvania, have invented 5 certain new and useful Improvements in Reeds for Looms, of which the following is a specification.

My invention relates to reeds for looms, 10 and it relates more particularly to the construction and arrangement of the dents of false reeds. The principal object of my invention is to provide a reed dent made from thin flat metal particularly adaptable for 15 use in false reeds which will wear indefinitely and will not require constant replacement as is necessary when the false reed is made from yarn as is now commonly practised. My invention also contemplates a 20 construction of the reed dents which, being slidable in the frame, will readily adjust themselves to any count of the warp, and the dents being made of thin flat metal while affording sufficient strength, the same will 25 not darken the point of operation nor crowd the warp in its passage therethrough. More 30 specifically considered my invention further contemplates a construction which permits a very close installation of the dents in the 35 frame:

The nature and characteristic features of my invention will be more readily understood from the following description taken in connection with the accompanying drawings forming part hereof, in which;

Figure 1 is a front elevation, partly broken away, of a reed having dents embodying the main features of my present invention mounted therein;

Fig. 2 is a transverse section of a portion of the frame taken on the line 2—2 of Fig. 1;

Fig. 3 is a similar section taken on the line 3—3 of Fig. 1; and

Fig. 4 is a perspective view, enlarged, of one of the reed dents detached.

Referring to the drawings, the reed dent constituting the principal element of my present invention is shown in enlarged per-

50 spective in Fig. 4 of the drawings and com-

prises a thin flat strip of metal substantially rectangular in cross section throughout the entire length of the strip of which the same is made and having its greater dimension in cross section extending in the same direction as the run of the warp through the loom. At each end of the dent, the metal strip is bent around without twisting out of the plane of the main body portion 5 to form loops or eyes 6, the thickness of which is consequently the same as that of said body portion 5, while the greater transverse dimension of the cross section at any portion of the eye is the same as that of the greater dimension of the cross section of said body 65 portion 5. By this arrangement it will be possible to mount the dents in very close relation while at the same time the loop or eye will be of sufficient strength for its required purpose.

The preferred manner of mounting the dents is shown in Figs. 1, 2, and 3 and consists preferably of a rectangular frame having top and bottom bars 8 preferably made of wood or similar material. The top and bottom bars 8 are provided with slots 11 through which the dents 5 extend and these slots 9 communicate with enlarged interior slots 12 within which the eyes 6 of the dents are mounted. The eyes 6 at each end of the 70 dents are threaded on a rod or bar 13, which extends from end to end of the frame bars 8 within the slots 12 and there are also provided two wires 14 which form hard bearing surfaces for the shoulders 15 of the 75 dents where the eyes 6 join the main body portion 5.

It will thus be seen that there is provided a reed construction particularly adaptable for false reeds in which the dents will be 80 strong and durable yet simple and inexpensive to manufacture, which are so constructed as to permit a very close installation, and which will be freely slidable in the frame, to thereby render the same adjustable to any count of the warp. Furthermore the dents will wear practically indefinitely and will not require constant replacement.

Having thus described the nature and 100

characteristic features of my invention, what I claim as new and desire to secure by Letters Patent is;

A reed dent formed of a strip of thin flat metal of a cross-section substantially rectangular and uniform throughout its entire length, with the greater dimension of the cross-section of the body portion ex-

tending in the same direction as the run of the warp, and having eyes at each end 10 formed by the strip being bent around in the same plane as the main body portion.

In testimony whereof I have hereunto signed my name.

JACOB KAUFMANN.
